US00D618172S

(12) **United States Design Patent**
Yang

(10) **Patent No.:** **US D618,172 S**
(45) **Date of Patent:** **** Jun. 22, 2010**

(54) **BATTERY CONNECTOR**

(75) Inventor: **Chih-Lin Yang**, Tu-Cheng (TW)

(73) Assignee: **Cheng Uei Precision Industry Co., Ltd.**, Tu-Cheng, Taipei Hsien (TW)

(**) Term: **14 Years**

(21) Appl. No.: **29/346,977**

(22) Filed: **Nov. 10, 2009**

(51) LOC (9) Cl. **13-03**

(52) U.S. Cl. **D13/120; D13/147**

(58) Field of Classification Search D13/103-106,
D13/118-121, 133, 154, 146-147, 184, 199;
439/83, 108, 166, 500, 577, 630, 660, 680,
439/700, 773.1, 862; 429/96-100, 163, 186

See application file for complete search history.

(57) **CLAIM**

The ornamental design for battery connector, as shown and described.

DESCRIPTION

FIG. 1 is a perspective view of a battery connector showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of the battery connector showing my new design.
